ATTORNEY.

UNITED STATES PATENT OFFICE

2,509,773

VALVE OPERATING MECHANISM FOR
REGISTERSRobert L. Leigh, Grand Rapids, Mich., assignor to
Air Control Products, Inc., Coopersville, Mich.

Application October 31, 1946, Serial No. 706,860

6 Claims. (Cl. 98—106)

1

This invention relates to improvements in valve operating mechanism for registers.

The main objects of this invention are:

First, to provide a valve operating mechanism for gravity registers in which the parts are simple and economical and easily assembled.

Second, to provide a valve operating mechanism for registers operated from a rotatable button or knob which is silent in operation. At the same time parts are effectively held in adjusted position even when the valve plate or damper plate is subject to considerable air flow.

Third, to provide a valve operating mechanism having these advantages effectively concealed within the register face and mounted as a part thereof to be applied as a unit to the register box.

Further objects relating to details and economies of the invention will appear from the description to follow. The invention is defined and pointed out in the claims.

A structure which embodies the features of the invention is illustrated in the accompanying drawing, in which:

Fig. 1 is a front elevation of a structure embodying my invention.

Fig. 2 is a rear or inside perspective view of a structure embodying my invention in vertical section on a line corresponding to line 2—2 of Fig. 1.

Fig. 3 is an enlarged fragmentary view partially in section on a broken line 3—3 of Fig. 2.

Fig. 4 is an enlarged fragmentary view in section on line 4—4 of Fig. 2.

In the accompanying drawing I have illustrated only the part of a register directly associated with my invention; that is, the register box or stack head is not illustrated.

The face plate designated generally by the numeral 1 is provided with rearwardly projecting side and top flanges 2 and 3 adapted to fit over parts of the register box. The damper or valve plate 4 is pivotally mounted at 5 on the inner side of the face plate. The face plate is provided with louver openings 6 at each side of the upright bar 7 preferably located centrally of the face plate. Screws indicated at 8 are provided to attach the face plate to the register box.

To the inner side of the bar 7 I secure the bridge member 9 having offset ends 10 and 11 which are welded to the inner side of the plate as indicated at 12. The knob or finger piece 13 is provided with a shaft 14 which is arranged through the face plate and the bridge and provided at its inner end with rack pinion 15. The rack member 16 is of angular section, its arm 17 constituting a slide, its arm 18 being provided

2

with a series of holes 19 forming rack teeth conformingly coacting with the pinion. The arm 17 is provided with longitudinal slots 21 and 22, these slots being longitudinally spaced, the slot 21 having an enlargement 23 at its lower end adapted to receive the pinion or permit the rack being manipulated over the pinion. The stud 24 carried by the bridge piece engages the slot 22 of the rack and holds the bowed spring 25 in frictional engagement with the rack to frictionally hold the rack in its adjusted position. This spring is secured to the stud after the stud is arranged through the slot.

The slot 22 is of such length that its ends serve as stops coacting with the stud to limit the sliding movement of the rack so that the pinion cannot be brought into register with the enlargement 23 of the slot 21. The valve plate 4 is provided with a longitudinal slot 26 and with a lug or ear 27 secured thereto to project rearwardly through the slot. This lug or ear 27 is connected by the link 28 to ear 29 on the rack member so that rotative adjustment of the knob 13 imparts sliding movement to the rack and this imparts swinging movement to the valve plate or damper 4.

The parts are effectively held in adjusted position throughout the range of adjustment, that is, from maximum to minimum and with the pivotal connections 29 and 30 for the link 28 reasonably tight the valve is supported without rattling or noise.

I have illustrated and described my invention in a practical embodiment thereof. No attempt has been made to show other adaptations which I contemplate, as it is believed that this disclosure will enable those skilled in the art to adapt or embody my invention as may be desired.

Having thus described my invention, what I claim as new and desire to secure by Letters Patent is:

1. The combination in a register of a face plate having a centrally disposed vertical bar portion, a bridge having forwardly offset ends secured to the inner side of said bar portion of said face plate, an adjusting knob provided with a shaft arranged through said face plate and bridge and rotatably supported thereby, a pinion on the rear end of said shaft, a rack member of angular section, one arm of which constitutes a slide and is slidably disposed on said bridge piece and provided with longitudinally spaced longitudinal slots, the upper one of which is provided with an enlargement at its lower end permitting the pass-

ing of the pinion therethrough, the other arm having a series of openings therein providing rack teeth coacting with the pinion, a stud carried by said bridge disposed through the lower slot, a bowed spring on said stud frictionally engaging the rack member for holding it in its adjusted position and coacting with the shaft and pinion to slidably support the rack upon the bridge piece, a swingably mounted valve having a vertical slot therein, a lug secured to said valve to project rearwardly therefrom, and a link disposed through said slot in said valve and pivotally connected to said lug and to said rack member whereby rotative adjustment of the knob imparts longitudinal movement to the rack member.

2. The combination in a register of a face plate having a centrally disposed vertical bar portion a bridge having forwardly offset ends secured to the inner side of said bar portion of said face plate, an adjusting knob provided with a shaft arranged through said face plate and bridge and rotatably supported thereby, a pinion on the rear end of said shaft, a rack member of angular section, one arm of which constitutes a slide and is slidably disposed on said bridge piece and provided with longitudinally spaced longitudinal slots, the upper one of which is provided with an enlargement at its lower end permitting the passing of the pinion therethrough, the other arm having a series of openings therein providing rack teeth coacting with the pinion, a stud carried by said bridge disposed through the lower slot, a bowed spring on said stud frictionally engaging the rack member for holding it in its adjusted position and coacting with the shaft and pinion to slidably support the rack upon the bridge piece, a swingably mounted valve and a link pivotally connected to said valve and to said rack member whereby rotative adjustment of the knob imparts longitudinal movement to the rack member.

3. The combination in a register, of a face plate, a bridge member secured to the inner side of said face plate, an adjusting knob provided with a shaft arranged through said face plate and bridge, a pinion on the rear end of said shaft, a rack member of angular section, one arm of which constitutes a rack coacting with the pinion, the other arm constituting a slide disposed on said bridge member and provided with longitudinally spaced longitudinal slots, one slot having an enlargement permitting the passing of the pinion therethrough, a stud on said bridge member disposed through the other slot, a bowed spring on said stud frictionally engaging the rack member for holding it in its adjusted position and coacting with the shaft and pinion to slidably support the rack upon the bridge member, a swingably mounted valve plate having a vertical slot therein, a lug secured to said valve plate to project rearwardly therefrom, and a link disposed through said slot in said valve plate and pivotally connected to said lug and to said rack member.

4. The combination in a register of a face plate, a bridge member secured to the inner side of said face plate, an adjusting knob provided

with a shaft arranged through said face plate and bridge, a pinion on the rear end of said shaft, a rack member of angular section, one arm of which constitutes a rack coacting with the pinion, the other arm constituting a slide disposed on said bridge member and provided with longitudinally spaced longitudinal slots, one slot having an enlargement permitting the passing of the pinion therethrough, a stud on said bridge member disposed through the other slot, a bowed spring on said stud frictionally engaging the rack member for holding it in its adjusted position and coacting with the shaft and pinion to slidably support the rack upon the bridge member, a swingably mounted valve plate and a link pivotally connected to said valve plate and to said rack member.

5. The combination in a register, of a valve member, a face plate, a bridge member secured to the inner side of said face plate, an adjusting knob provided with a shaft arranged through said face plate and bridge, a pinion on the rear end of said shaft, a rack member of angular section, one arm of which constitutes a rack coacting with the pinion, the other arm constituting a slide disposed on said bridge member and provided with longitudinally spaced longitudinal slots, one slot having an enlargement permitting the passing of the pinion therethrough, a stud on said bridge member disposed through the other slot, a spring on said stud frictionally engaging the rack member for holding it in its adjusted position and coacting with the shaft and pinion to slidably support the rack upon the bridge member, and operating connections from said rack for said valve member.

6. In a register, a valve member, a face plate, a bridge member secured at the ends thereof to the inner side of said face plate and spaced from the face plate intermediate the ends of the bridge member, an adjusting knob provided with a shaft arranged through said face plate and bridge member, a pinion on the rear end of said shaft at the rear of said bridge, a rack member of angular section, one arm of which projects rearwardly and constitutes a rack coacting with the pinion, the other arm constituting a slide slidably mounted on the rear side of said bridge member, a spring frictionally engaging the rack member for holding it in its adjusted position on said bridge member, and operating connections from said rack for said valve member, said bridge member rotatably supporting said shaft between said pinion and face plate and in spaced relation from said face plate.
